UNITED STATES PATENT OFFICE.

PAUL HUEETHER, OF PITTSBURGH, PENNSYLVANIA.

FOUNTAIN-BRUSH.

1,226,520.

Specification of Letters Patent. Patented May 15, 1917.

Application filed August 3, 1916. Serial No. 112,924.

To all whom it may concern:

Be it known that I, PAUL HUEETHER, a citizen of the United States, and resident of Pittsburgh, in the county of Allegheny and State of Pennsylvania, have invented a new and useful Improvement in Fountain-Brushes; and I do hereby declare the following to be a full, clear, and exact description thereof.

10 My invention relates to fountain-brushes, and more particularly to a brush for applying blacking to shoes.

15 The object of my invention is to provide a compact, durable form of brush in which the receptacle containing the blacking material is located within the handle in such a way as to be securely held therein, and yet freely removable when desired, provision being made for discharging the liquid 20 from the receptacle when desired.

A further object of my invention is to provide a device in which the valve controlling the discharge of the liquid will not ordinarily become clogged up to prevent the 25 discharge of liquid and in event of so doing can be readily removed and cleaned.

To these ends my invention comprises the novel features hereinafter set forth and claimed.

30 In the drawing, Figure 1 is a longitudinal section of my improved brush; Fig. 2 is an end view; and Fig. 3 is a cross section on the line 3—3, Fig. 1.

The numeral 2 designates the handle of 35 my improved brush which is preferably made in two parts 3 and 4 connected by the bolts 5 whose heads fit in countersunk openings 6 and 7. In order to provide for certain expansion of the parts of handle in 40 inserting the can containing the liquid, one end of the bolt is surrounded by the spring 8 inclosed between the head of said bolt and the shoulder 9 of the countersunk opening.

The brush handle is provided with the ordinary bristles 10.

The parts 3 and 4 composing the handle have the concave faces 11 which together form a circular seat or housing for the can or receptacle 12 containing the liquid. This 50 can is held securely in position due to the action of the springs 8 and fits snugly within the parts of the handle. The parts of the handle are slightly expanded in order to force the can into its seat.

55 The can is provided with the plug 13 at one end which may be formed of cork,

wood, or any other suitable material. This plug is formed with the passage 15 extending through it, said passage registering with the openings 16 and 17 in the can. 60

A valve casing 18 extends through the openings 16 and 17 and through the passage 15 in the plug, the inner end 19 of said valve casing extending beyond the opening 30 in the inner face of the handle into position to 65 discharge the liquid onto the bristles at that end of the brush. The valve casing has the valve seat 20 for the valve 21 carried by the stem 22. A spring 23 surrounds the stem 22, said spring being interposed between the shoulder 24 in the valve casing and the head 25. This spring normally holds the valve in closed position. By pressing down on the head 25, the valve 21 is unseated. The valve-casing 18 extending as it does through 70 the openings in the can, the passage in the plug, and through the handle acts to hold the can securely in place against longitudinal movement in the handle, while at the same time the plug is locked in position. 75

The valve-casing has the head 26, said head having the notch 27 which indicates when the opening 28 in the valve-casing is in register with the opening 29 in the plug 13. In Fig. 1 the said openings are in register 80 and it is apparent that by turning the head 26 the valve casing will be moved and the solid portion moved around to close the opening 29 when it is desired to cut off all communication from the can and prevent 85 the accidental discharge of the liquid therefrom.

When it is desired to discharge liquid from the can, the valve-casing is first turned by turning the head 26 until the opening 28 90 is brought into register with the opening 29, whereupon, by pressing the finger on the head 25 the valve 21 is unseated and the operator then by slightly shaking the can will cause the liquid in the can to pass down 95 through the valve casing to be discharged from the extension 19 onto the bristles. In this way the brush not only acts as a dauber, but also as a brush for polishing. If, at any time the bristles at the one end become 100 worn, the can may be reversed as I have provided openings 30 at each end of the brush for the passage of the valve casing, and the valve may be used at either end with equal 105 facility.

110 The location of the valve enables the operator to grasp the brush firmly and at the

same time permits him to place one finger upon the valve head to operate the valve, and the supply of liquid is shut off automatically just as soon as the finger is released from the valve-head, so that there is no chance for the wasting of the liquid as it is only supplied in the quantities desired.

Furthermore, by having the valve-casing capable of turning in the way illustrated and described, a double check is had on the discharge of the fluid.

It is apparent that when the liquid has been exhausted, the can may be removed and a new one readily inserted, the cans being supplied with the plugs 4, and the openings 16 and 17 can be plugged up, said plugs to be removed when the valve-casing is inserted.

In case the valve should in time become clogged up, the valve casing may be removed and by inserting the same in some cleansing fluid, the parts are cleaned and restored to their original condition.

What I claim is:

- 25 1. In a fountain brush, the combination of a two-part expansible handle having bristles, a liquid-container held between said parts, said container having a valve-controlled opening whereby liquid may be discharged therefrom.
- 30 2. In a fountain brush, the combination of a handle having bristles formed of two

parts forming a seat between the same, yielding connections between said parts, a liquid-container held between said parts, 35 said container having a valve-controlled opening whereby liquid may be discharged therefrom.

3. In a fountain brush, the combination of a handle having bristles formed of two 40 parts, bolts connecting said parts, and springs surrounding said bolts interposed between heads on said bolts and shoulders formed in said handle, a liquid-container held between said parts, said container having valve-controlled openings whereby said liquid may be discharged therefrom.

4. In a fountain brush, the combination of a handle having bristles and having a cavity extending longitudinally thereof, a liquid container fitting within said cavity, a plug in said container having a passage extending through it, a rotary valve casing extending through said passage and through an opening formed for it in said handle, 50 and a spring-controlled valve in said casing.

In testimony whereof, I the said PAUL HUETHER, have hereunto set my hand.

PAUL HUETHER.
